H. RODGERS.

RAIL BENDER.

APPLICATION FILED DEC. 1, 1920.

1,425,135.

Patented Aug. 8, 1922.

UNITED STATES PATENT OFFICE.

HUGH RODGERS, OF SULLIVAN, INDIANA.

RAIL BENDER.

1,425,135.

Specification of Letters Patent. Patented Aug. 8, 1922.

Application filed December 1, 1920. Serial No. 427,590.

To all whom it may concern:

Be it known that I, HUGH RODGERS, a citizen of the United States, residing at Sullivan, in the county of Sullivan and State of

5 Indiana, have invented certain new and useful Improvements in Rail Benders, of which the following is a specification.

This invention relates to rail benders and is an improvement on my application filed 10 September 27, 1919, Serial No. 326,747, allowed April 22, 1920.

An important object of this invention is to provide novel means for mounting the ratchet wheel on the tensioning screw in such 15 a manner that the side thrust on the ratchet wheel is effectively taken up so that the operation of the rail bender will be rendered easier.

A further object of the invention is to 20 provide a rail bender of the character set forth in my previous application and which is provided with a simple guard arrangement adapted for protecting the ratchet wheel.

25 A further object of the invention is to provide a rail bender having novel means for mounting the handle in such a manner that the same may be operated in either direction.

30 A further object of the invention is to provide a rail bender which is simple to operate, efficient in use and cheap to manufacture.

Other objects and advantages of the 35 invention will be apparent during the course of the following description.

In the accompanying drawing forming a part of this application and in which like numerals are employed to designate like 40 parts throughout the same,

Figure 1 is a fragmentary plan view of the improved rail bender;

Figure 2 is a fragmentary side elevation of the same;

45 Figure 3 is a vertical transverse sectional view taken on line 3—3 of Figure 1;

Figure 4 is a vertical transverse sectional view of the preferred form of rail bender.

In the drawing, the numeral 30 generally 50 designates a beam having its forward portion curved longitudinally to form a laterally projecting arm 31 which as illustrated in Figure 1 is provided with a socket 32 adapted for the reception of a portion of 55 a rail to be bent. The intermediate portion of the beam is provided with a transverse

opening through which a tensioning screw 33 extends. The forward portion of the tensioning screw 33 is formed with a socket 34 also adapted for the reception of a portion of the rail to be bent. A nut 35 is threaded onto the tensioning screw 33 on opposite sides of the beam and is employed when it is desired to adjust the socket 34 with relation to the socket 32 when preparing the apparatus for use.

As illustrated in Figure 1, the rear end portion of the beam is somewhat enlarged and is formed with a longitudinally extending opening 36 within which a ratchet wheel 37 generally designated by the numeral 37 is arranged. The ratchet wheel 37 is as illustrated in Figure 3 formed with an interiorly screw threaded opening 38 which is aligned with openings 39 formed in the side walls 40 of the opening 36 whereby a second tensioning screw 41 may be extended transversely through the beam in spaced parallel relation to the tensioning screw 33.

When the ratchet wheel 37 is rotated the 80 tensioning screw 41 will, of course, be moved longitudinally so as to bend the rail seated within the sockets 32, 34 and the socket 42 formed in the forward end of the tensioning screw.

The means for rotating the ratchet wheel in the desired direction comprises a pair of spaced parallel straps 43 secured to opposite sides of the attaching shank 45 of a handle member 46 by means of spaced bolts 47. The forward portions of the straps 43 are enlarged and are of annular formation, as indicated at 48, so that the same may be arranged on opposite sides of the ratchet wheel outwardly of annular shoulders 50 formed on the ratchet wheel. Therefore, it will be apparent that the ratchet wheel serves as a supporting means for the handle 46. A double acting pawl 52 pivoted to the straps 43 by means of a pivot bolt 53 is adapted for engagement with the teeth of the ratchet wheel so that a movement of the handle about the axis of the tensioning screw 41 will result in the rotation of the ratchet wheel.

Washers 54 are arranged between the sides of the ratchet wheel and the opposite sides of the opening 36 and act as anti-friction elements during the operation of the device.

In the preferred form of the invention illustrated in Figure 4, the side walls are

increased in width and extend beyond the peripheries of the spaced annuli 48 so that anti-friction rollers 55 will be arranged between the opposite sides of the annuli and 5 the walls 40. The anti-friction rollers 55 are, of course, seated in annular grooves 56 in opposite sides of the annuli and the walls 40. By reason of this construction the strain 10 on the ratchet wheel is effectually taken up so that the device may be operated without excessive effort on the part of the operator.

As illustrated in Figure 2, the ratchet wheel 37 is provided with a longitudinally curved guard 60 which has its ends secured 15 to the beam. The guard 60 prevents the teeth of the ratchet wheel from engaging the ground and possibly picking up stones and the like.

With reference to the foregoing description taken in connection with the accompanying drawing, it will be apparent that a rail bender constructed in accordance with this invention may be operated by one man 20 since the friction on the several parts is reduced to a minimum.

Having thus described the invention, what is claimed as new is:

In a rail bender having an L-shaped beam with rail-engaging jaws formed at the end

of its short arm, a transverse aperture and 30 circular holes communicating therewith adjacent the end of its long arm, a connecting wall being formed at its extreme end, and the intermediate portion of said long arm being provided with an opening running 35 parallel with said holes and with said short arm, the combination with a pair of rail-gripping members having threaded shanks, one of said members engaging in said opening, and nuts for adjustably securing said 40 first member therein, the second member engaging in said holes, a bifurcated operating handle fitting with its prongs in said aperture and around said second member, an internally threaded ratchet wheel engaging 45 with said second member between said prongs, a pawl hinged on said handle adapted to engage with said ratchet wheel, and roller bearings inserted between the internal surface of said aperture and said prongs on 50 the handle, and an arcuate guard plate covering the teeth of said ratchet wheel protruding on one side of said aperture, said guard plate being rigidly secured to said connecting wall and to the body of said 55 L-shaped beam.

In testimony whereof I affix my signature.

HUGH RODGERS. [L. s.]
